CLAIM

The ornamental design for an automotive vehicle, as shown and described.

DESCRIPTION

FIG. 1 is a front perspective view of an automotive vehicle embodying the design;

FIG. 2 is a rear perspective view thereof;

FIG. 3 is a right side elevational view thereof;

FIG. 4 is a left side elevational view thereof;

FIG. 5 is a front elevational view thereof; and,

FIG. 6 is a rear elevational view thereof.

The top of the automotive vehicle is understood to be substantially plain and unornamented.
